UNITED STATES PATENT OFFICE.

ADÈLE AMÉLIE LONGUEMARE, OF PARIS, FRANCE.

CARBURETER FOR EXPLOSIVE-ENGINES.

No. 875,716.

Specification of Letters Patent.

Patented Jan. 7, 1908.

Application filed November 11, 1905. Serial No. 286,878.

To all whom it may concern:

Be it known that I, ADÈLE AMÉLIE LONGUEMARE, a citizeness of the Republic of France, residing at Paris, in France, have 5 invented certain new and useful Improvements in or Relating to Carbureters for Explosion-Engines, of which the following is a specification.

This invention relates to a carbureter in 10 which additional introduction of a quantity of fresh air required for the proper formation of the explosive mixture is effected, for the initial formation of the mixture, by means of a valve surrounding in an annular manner, 15 the ordinary air inlet nozzle, the lift of which valve for supplementary admission of air can be regulated by means of a stop operated as desired.

In the accompanying drawing:—Figure 1 20 is a vertical section of a carbureter according to this invention, the regulating part of the supplementary air inlet valve being shown in the position corresponding to that of complete closing of the said valve. Figs. 2, 3, 25 and 4 are sectional elevations of the valve with its regulating part in four principal positions: complete and maintained closing (Fig. 2), automatic and regulated working (Fig. 3), complete automatic working (Fig. 4 30 full lines), complete maintained opening (Fig. 4 dotted).

According to this construction, the double-conical choke tube *a* of well known construction, in the interior of which the combustible 35 mixture is produced, is combined with a valve *b* surrounding in an annular manner the said choke tube *a*, so that it can slide with a slight amount of friction in the cylindrical body *l* of the carbureter. In this construction the double-conical choke tube *a* is provided at its large lower base with a sleeve *m* 40 surrounding the tubular body *n* of the atomizer pipe *j*, and the said large base is provided with a series of holes *i* freely admitting 45 into the interior of the choke tube *a*, air which penetrates into the carbureter through the bottom openings *o* made in its corresponding plate.

The seat surface of the additional valve *b* 50 is constituted by the angle formed by a reduced cylindrical portion *d* with which it is provided in the center of its height. In the position of rest of the valve *b*, the said angle rests against the outer circumference of the 55 double conical choke tube *a* along a circle situated near its large base.

The valve *b* is forced against its seat by the tension of a weak spring *c* resting, on the one hand, against the interior of the upper collar of the said valve, and, on the other hand, 60 against the bottom surface of the cover of the casing *l* of the carbureter.

In the annular hollow space left between the two collars *s* of the valve *b*, which is thus made into a piston of the carbureter, and at a 65 point of the annulus or reduced portion *d*, can swing an arm *e* secured to one of the ends of a pin *f*. The latter is mounted in a plug *p* screwed into the body *l* of the carbureter and carries at its outer end (relatively to the 70 said carbureter), another arm *g* which can be operated by any suitable gear, so as to produce oscillation of the arm *e*, in order to bring it into any desired position. In its vertical downward position (Figs. 1 and 2), 75 the arm *e* rests with its end against the bottom collar *s* of the valve *b*, so as to hold it applied against its seat *h* for maintaining it completely closed. The arm *e* placed obliquely as in Fig. 3, enables the valve *b* to 80 lift to a limited extent under the influence of the suction, the result being regulation of the admission of additional air.

The arm *e*, placed horizontally as in Fig. 4, 85 enables the valve *b* to act in an absolutely automatic manner under the action of the suction, from its closing up to its maximum opening. Finally, the arm placed vertically upwards, as shown dotted in Fig. 4, maintains the valve in its maximum opening 90 position. It will be seen from this arrangement that if the valve *b* is secured to its seat *h* by means of the arm *e* (Figs. 1 and 2), the reduction of pressure which takes place in the suction pipe *k*, is transmitted fully into 95 the double conical choke tube *a* and acts with its full force on the fuel escaping from the nozzle *j*, as well as on the column of air entering through the openings *o* and *i*, any other admission of additional air being pre- 100 cluded.

If it is desired to obtain a weaker explosive mixture, without however altering the volume of carbureted air, the arm *e* is turned so as to put it into a given oblique position, as 105 shown in Fig. 3. In that position the valve *b* will be released in such manner that, under the influence of the suction taking place in the carbureter, and according to the degree of the said suction, the said valve will be 110 lifted from its seat, which will enable air to be introduced into the annular ring formed

by the space separating it at that moment from its seat.

It must be pointed out that any additional air does not increase the supply of combustible liquid but on the contrary lessens the same since it diminishes the volume passing through the said choke tube.

In order to make the admission of air perfectly automatic, it is sufficient, as already 10 stated, to place the arm *e* horizontally as shown in full in Fig. 4.

What I claim as my invention and desire to secure by Letters Patent is:—

1. In a carbureter the combination of an 15 atomizer for the fuel, a choke tube surrounding the atomizer said choke tube comprising the frusta of two hollow cones connected by their smaller ends, a valve seat formed by the base of the lower frustum, a supplemental air valve adapted to fit the valve seat 20 on the choke tube, an inclosing casing surrounding the air valve, a helical spring arranged between the top of the valve and the casing and adapted to press the valve upon its seat, said spring being capable of being overcome by a reduction of pressure within the casing, and means for controlling the 25 movement of the valve substantially as set forth.

2. In a carbureter the combination of an 30 atomizer for the fuel, a choke tube surrounding the atomizer said choke tube comprising the frusta of two hollow cones connected by their smaller ends, a valve seat formed by the base of the lower frustum, a supplemental 35 air valve comprising a hollow piston having an annular internal projection said projection being adapted to fit the valve seat

on the choke tube, an inclosing casing surrounding the air valve, a helical spring arranged 40 between the top of the valve and the casing and adapted to press the valve upon its seat, said spring being capable of being overcome by a reduction of pressure within the casing and means for controlling the 45 movement of the valve substantially as set forth.

3. In a carbureter the combination of an atomizer for the fuel, a choke tube surrounding the atomizer said choke tube comprising the frusta of two hollow cones connected by their smaller ends, a valve seat formed by the base of the lower frustum, a supplemental air valve comprising a hollow piston having a reduced cylindrical portion forming 50 an external annular groove and an internal projection, said projection being adapted to fit the valve seat on the choke tube, an inclosing casing surrounding the air valve, a helical spring arranged between the top of 55 the valve and the casing and adapted to press the valve upon its seat, said spring being capable of being overcome by a reduction of pressure within the casing, a stop-arm adapted to engage the external annular groove of 60 the hollow piston forming the air valve, a pin carrying the said stop-arm, a bearing for the pin, and an operating arm on the outer end of the pin, substantially as set forth.

In testimony whereof I have signed my 70 name to this specification in the presence of two subscribing witnesses.

ADELE AMÉLIE LONGUEMARE.
